UNITED STATES PATENT OFFICE.

CARL W. GREGORY, OF PETALUMA, CALIFORNIA.

TRACK LAYER FOR TRUCKS.

1,404,520.

Specification of Letters Patent. Patented Jan. 24, 1922.

Application filed July 21, 1919. Serial No. 312,441.

To all whom it may concern:

Be it known that I, CARL W. GREGORY, a citizen of the United States, and a resident of the city of Petaluma, county of Sonoma,

5 State of California, have made a new and useful invention—to wit, Track Layers for Trucks; and I do hereby declare the following to be a full, clear, concise, and exact description of the same.

10 The present invention is an attachment for motor trucks, and contemplates the use of tracklaying units which are substituted for the rear or drive wheels of said truck.

15 The primary object of the invention is to provide attachments of new and novel construction as regards the spring suspension. The novelty in construction and operation of my device lies in the double spring suspension. The forward springs being carried by a truss, as hereinafter described, co-operate with the spring suspension already installed on the truck, and through the agency of both of the interposed springs between both ends of tracklaying attachment

20 and the load, provide means which will operate in a reverse direction, and which will act while being driven in either direction independently of the inclination of the body of the truck.

25 30 A further object is to construct and apply track laying units in such a manner that the center of gravity of the load carried by said units may be automatically shifted with respect to its bearing point on the truck; thereby causing the vehicle to negotiate changes in its plane of operation without interfering with the forward movement of the track laying units.

In this specification and the annexed drawings, the invention is illustrated in the form considered to be the best, but it is to be understood that the invention is not limited to such form, because it may be embodied in other forms and it is also to be understood that in and by the claims following the description it is desired to cover the invention in whatever form it may be embodied.

In the drawings:

35 40 Figure 1 is a top plan view of a truck with my invention applied thereto.

Figure 2 is a side elevation of one of my track laying attachments for a truck.

45 50 Figure 3 is a cross section taken on the line III—III of Figure 5.

Figure 4 is a detail view showing the manner of attaching the forward end of a track laying unit to a truck (only one attaching means being shown).

Figure 5 is a side elevation of a truck of conventional type with my attachment installed thereon.

Referring to the drawings in detail, the numerals 1 and 2 indicate the sills of a motor truck, while the numerals 3, 4, 5, 6 and 7 refer to cross braces connecting said sills. This frame so formed carries a power unit 8 having a shaft 9 extending rearwardly. The usual front axle 10 is provided which carries wheels 11 and 12 capable of being steered. This axle is secured to the front of the vehicle by suitable springs, not shown.

55 At 13, I have shown a rear axle housing having the usual differential and enclosing a horizontal shaft which secures its power from the propeller shaft 9 and suitable differential gears. Springs 14 and 15 are supported by the axle housing and have suitable connections with said frame.

60 65 All of the description thus far refers to a standard type of truck (as differentiated from tractors) which is adapted to haul various commodities, and is the type of truck upon which I wish to employ my track laying units in substitution for the usual wheels. 70 These track laying units are here shown by the numerals 16 and 17. One of these track laying units is best shown in side elevation on an enlarged scale in Figure 2 and represents the track laying unit marked 16 in 75 Figure 1.

75 80 For purposes of simplicity I will describe but one unit, adapted to replace a wheel on one side of the truck, it being understood that the unit on the opposite side is a duplicate with the exception that it is arranged to be employed upon the left hand side of the machine instead of the right.

85 90 In construction, these units consist of two parallel channel irons 18 and 19 Figure 3. 100 These channel irons are attached at their forward end by a casting 20 suitably bolted thereto. The forward ends support the lower halves 21 of keeper plates. These keeper plates have caps 22 and are slidably held 105 by yokes 23. These plates are in axial alignment and fixedly secured to a short horizontal shaft 24 carrying a flanged hub 25 rotating freely thereon, which carries a sprocket wheel rim 26. The sprocket wheel rotates 110

between the ends of the channel irons 18 and 19. The opposite ends of these channel irons carry the lower portions of bearing blocks 27 (Figure 3) to which are attached 5 bearing caps 28 by means of U bolts 29 passing over the same and engaging the underside of the channel irons 18 and 19. The bearings thus formed upon each channel iron are in axial alignment and are adapted 10 to carry a tubular member 30 having a radical flange 31 which is approximately in the center of the tubular member. Said flange carries a sprocket wheel rim 32 suitably secured thereto. This sprocket wheel 15 rim may be made integral or detachable, as shown at 33. This tubular member 30 is provided at the end adjacent the truck with a flange 34, and at its opposite end with a flange 35. Bolted to the under sides of 20 the channel members 18 and 19 are keeper plates 36, 37 and 38 (Figure 2) which rigidly secure shafts 39, 40 and 41 upon which are mounted freely rotating idlers 42, 43 and 44, the purpose of which will be hereinafter seen. Mounted between the bearings 25 21 and 27 I provide a U-shaped frame 45 upon each channel iron, which is suitably braced by braces 46 and 47. These U-shaped members support keepers 48 which are 30 in axial alignment and rigidly secure a shaft 49 upon which is mounted an idler 50. The sprockets 26 and 32 are in alignment so as to accommodate a chain made up of links 51 35 and 52 carrying treads 53. This endless chain passes over the sprocket wheel 26, thence under the idlers 44, 43 and 42 forming a track therefor and also a support for the entire device, thence over the 40 sprocket 32 and idler 50. Any slack of the chain may be taken up by turning the adjusting screws 54 which will move the keeper plates 21 forward on their channel bars thus effecting a tightening of the links 45 composing the chain.

In the present instance, I have shown my track laying units upon a truck having what is commonly known as a live axle. It is obvious, however, that the same may be 50 employed with trucks of the dead axle type, as well as with those termed "floating," without departing from the spirit of my invention.

In assembling my invention on a motor truck, it is necessary to disconnect the axle shaft drive plate from the hub flange on 55 the rear wheel. The axle shaft, which is floating, is then withdrawn, after which the lock nuts which secure the wheel to the shaft housing are removed and the wheel taken off. I then substitute for these parts 60 removed, the assembly shown in Figures 2 and 3.

This is accomplished by sliding the part 65 30 upon the shaft housing. The lock nuts

which held the wheel in place are then replaced and tightened. A new axle is then inserted in the place of the one removed. This new axle carries a drive plate having an outwardly flaring flange which 70 is attached by suitable bolts to the flange 35, as shown.

Referring now to Figure 4, I provide an I-beam 62 placed horizontally and in transverse relation to the sill members 1 and 2. 75 This I-beam projects beyond the line of said sills and is attached thereto by means of bolts 63 passing through Z shaped keepers 64 on which are journaled rollers 65. These rollers contact with the flanges of 80 said sill members and slidably support said I-beam 62. The outer ends of these I-beams are provided with adjustment openings 66 which allow angle members 67 to be moved laterally to accommodate different widths 85 of tread. These angle members 67 carry vertically adjustable yoke members 68 adjusted through the medium of bolts 69 and openings 73. The outer ends of these yoke members are adapted to overlie and underlie the center of the cast members 20, so that a bolt 70 passed through each yoke will pass through said cast members 20. The bolt 70 carries a spring 71 above the member 20 and a spring 72 below said member 90 20, the purpose of which will be herein-after described.

In vehicles not provided with torque rods or truss rods there is a slight movement of the rear axle longitudinally with relation 100 to the frame of the truck, which movement is related to the movement of the springs through which the thrust is applied. In other words, the forward half of the semi-elliptic spring buckles under the strain 105 of propulsion as applied through the axle at the center of said spring.

When an incline or heavy going is encountered, the movement just referred to becomes greater. It is to accommodate this 110 movement that the I-beam 62 is provided with rollers engaging the sills of the truck frame. This I-beam and the yokes attached thereto also perform another function which will be later seen.

As the track laying units are connected to the rear axle housing, the same forms a pivot point for the units in order that they may have free movement in negotiating rough ground. The action of my unit is as 120 follows:—

Referring now to Figure 5, in which the truck is shown on level ground, I wish to describe an action which is peculiar to this construction, and which is of decided importance in my invention. It is a well known fact that in motor truck construction, the forward axle supports a relatively 125 small proportion of the weight of the load, approximately 20 per cent. A study of 130

Figure 5 will show that the greater part of the load, indicated in dotted lines thereon, would be supported on the rear axle if same were provided with the usual wheels. With 5 the unit substituted herein, the weight will be distributed proportionately between said axle and the springs 71. These springs 71 are of sufficient strength to force the tread elements downward to contact with the 10 ground irrespective of the position of the body truck.

It results from this construction that should the track-laying element be on hard ground, and the forward wheels encounter 15 soft ground or a depression in the surface and settle slightly, as indicated by the dotted lines, the springs 70 will receive the major portion of the load and act as a fulcrum over which the truck and load is balanced. This 20 action is peculiar to the structure here shown, and is decidedly beneficial. The action described is decidedly perceptible to a rider on the seat of the truck. When the forward wheels encounter soft ground, as before described, the truck settles at the forward end 25 slightly, and is felt to rise as the weight of the load shifts to the spring 70. The driving power of the tracklayers tends to lift the forward end of the truck out of a depression rather than to dig deeper as is the case 30 with tracklaying attachments which are pivoted or journalled to the rear axle.

The springs 70 are so arranged that they co-operate with the semi-elliptical springs 35 connected to the rear axle housing in such a manner that this action just described becomes automatic.

The advantage in the application of power 40 is obvious, as in negotiating an inclination or in passing from an up grade to a down grade the center of the load automatically shifts to a position best suited to the requirements of the tractor element.

Having thus described my invention what 45 I claim as new and desire to secure by Let-

ters Patent of the United States is as follows:—

1. A motor vehicle comprising a frame, a motor mounted on said frame, an axle housing resiliently mounted on said frame, an axle carried by said housing and geared to said motor, track laying units journalled at one end and driven by said axle, a transverse bar beneath said vehicle and in slidable contact therewith, resilient supports connecting the ends of said bar and the forward ends 55 of said units, said supports being capable of carrying the load of said vehicle.

2. A motor vehicle comprising a frame, a motor mounted on said frame, an axle housing resiliently mounted on said frame, an axle carried by said housing and geared to said motor, track laying units pivoted at one end to said housing and driven by said axle, a transverse bar beneath the said frame and 60 in slidable contact therewith, springs interposed between the forward ends of said track laying units and said bar, said springs being capable of supporting the load of the said vehicle, and said springs being capable 65 of movement independent of that of the said frame.

3. A motor vehicle comprising a frame, a transverse driven axle resiliently mounted 75 on said frame, track laying units pivoted concentrically with said axle, traction mechanism on said units connected to said axle, resilient supports interspaced between said vehicle frame and the forward end of said units, said supports being movable longitudinally with relation to said frame and capable of supporting the load on said vehicle.

In testimony whereof, I have hereunto set my hand at San Francisco, California, 85 this 11th day of July, 1919.

CARL W. GREGORY.

In presence of—
A. J. HENRY.
